UNITED STATES PATENT OFFICE.

FRANK F. BURTCII, OF FONDA, NEW YORK.

DESIGN FOR A BROOM-HANDLE.

SPECIFICATION forming part of Design No. 28,121, dated January 4, 1898.

Application filed November 6, 1897. Serial No. 657,704. Term of patent 14 years.

To all whom it may concern:

Be it known that I, FRANK F. BURTCII, a citizen of the United States, residing at Fonda, in the county of Montgomery and State of New York, have invented a new and original Design for Implement-Handles, of which the following is a specification.

This invention relates to a new and original design for broom or similar handles, and is illustrated in the accompanying drawings, in which—

Figure 1 is an elevation, and Fig. 2 is a section, of a broom-handle.

As shown in the drawings, the leading and distinguishing feature of my design consists in a broom-handle having a plurality of diagonally-running or spiral stripes, which, as shown in the drawings, begin at the end of the handle to which the broom-head is secured and extend around said handle in a right-hand direction spirally or diagonally to the top of the grasping end of the handle, and other stripes which also extend from the end of the handle to which the broom-head is secured in a left-hand direction around said handle spirally or diagonally to the grasping end, the stripes being of different or distinguishing colors.

In the said drawings the reference-numeral 1 designates the handle and 2 and 3 the stripes, which begin at the end of the handle to which the broom-head is secured and extend around said handle in a right-hand direction spirally or diagonally to the top of the grasping end of the handle, and 4 and 5 designate the stripes which extend from the end of the handle to which the broom-head is secured in a left-hand

direction around said handle spirally or diagonally to the grasping end.

The stripes 2, 3, 4, and 5 are of different or 40 distinguishing colors. As shown in the drawings, the stripes 2 and 4 are of a blue color, which is indicated by showing said stripes in Fig. 2 of the drawings by a series of longitudinal lines, and the stripes 3 and 5 are of 45 a red color, which is indicated in said Fig. 2 of the drawings by a series of cross or transverse lines.

While I have described and shown the colors of the stripes as of red and blue, I wish 50 it understood that my design is not limited to any particular colors of the stripes.

While I have shown the stripes described extending over the entire length of the handle, I desire it to be understood that I do not 55 confine myself to such precise arrangement, as the stripes may extend for a portion or portions only of the length of the handle and yet be within the scope of my invention.

My design presents a broom or similar handle having an attractive, ornamental, and distinctive appearance. 60

Having thus described the invention, what I claim is—

The design for a broom or similar handle 65 as herein shown and described.

In testimony whereof I have hereunto set my hand in presence of two subscribing witnesses.

FRANK F. BURTCII.
